UNITED STATES PATENT OFFICE.

HERMAN R. SAXON AND GEORGE GANZERT, OF TOLEDO, OHIO, ASSIGNEES TO THE SAXON MANUFACTURING COMPANY, OF TOLEDO, OHIO, A CORPORATION OF OHIO.

FUEL-FEEDING DEVICE.

1,325,701

Specification of Letters Patent. Patented Dec. 23, 1919.

Application filed June 11, 1917. Serial No. 174,107.

To all whom it may concern:

Be it known that we, HERMAN R. SAXON and GEORGE GANZERT, citizens of the United States, residing at Toledo, in the county of Lucas and State of Ohio, have invented certain new and useful Improvements in Fuel-Feeding Devices, of which we declare the following to be a full, clear, and exact description.

10 This invention relates to improvements in fuel feeding devices for automobiles, of the type embodied in our copending application filed June 11, 1917, Serial Number 174,108. The present invention relates particularly 15 to improvements in devices of the type in which the fuel is fed from a main low-level supply tank to an elevated vacuum tank by means of the vacuum created in said tank through a connection with the intake manifold of an engine, the fuel being fed from the vacuum tank by gravity to the carbureter. The principal object of our invention is to provide in such a vacuum tank an improved arrangement of the valves and 25 valve operating mechanism. A further object of our invention is to provide an improved vacuum tank construction, which can be constructed very conveniently, and at low cost, and which can be produced and 30 assembled in large quantities with great economy.

Further objects, and objects relating to economies of manufacture and details of construction will definitely appear from the detailed description to follow.

We accomplish the objects of our invention by the devices and means described in the following specification. Our invention is clearly defined and pointed out in the appended claims.

A structure, constituting a preferred embodiment of our invention, is illustrated in the accompanying drawing forming a part of this specification, in which:

45 Figure I is a diagrammatic view of a vacuum tank constructed in accordance with our invention, showing the connections with the main fuel supply tank, and with the intake manifold and carbureter of the engine. Fig. II is a vertical, sectional view through a vacuum tank constructed in accordance with our invention, showing the valve in position to connect the tank with the source of suction. Fig. III is a fragmentary, detail view, partly in section and

partly in side elevation, showing the valve mechanism with the valve in position to connect the tank with the atmosphere and to close the connection with the source of suction. Fig. IV is a sectional view, taken substantially on the line IV-IV of Fig. II.

In the drawings, similar reference numerals refer to similar parts throughout the several views, and sectional views are taken looking in the direction of the little arrows at the ends of the section line.

Considering the numbered parts of the drawings, it will be seen that our fuel-feeding system comprises a vacuum tank 10, which is connected with a main low-level supply tank 13, by means of a fuel conduit 14. The vacuum tank is also connected by the conduit 16, with a source of suction such as the intake manifold of an internal combustion engine 15, said conduit 16 being preferably connected to the manifold at a point adjacent the carbureter. The tank 10 is also connected, by fuel passage 18, with the carbureter, so that fuel feeds by gravity from the tank to the carbureter 17.

Our improved vacuum tank comprises a main float chamber 19, and an auxiliary chamber 20, which latter chamber is open at the top and provided with a flange 23, on which is disposed a gasket 24, the auxiliary chamber 20 being closed by the bottom of the main float chamber 19, which rests on the gasket 24, the main float chamber and auxiliary chamber being secured together as a unit. Float chamber 19 has a cover 25

carrying a gasket 26 interposed between the top rim of the chamber 19 and the cover. Stem 27 is disposed axially of the main float chamber 19 and has its lower and upper ends threaded and extending through the bottom of the main float chamber 19 and the cover 25 respectively. The elbow 28 is screwed on to the threaded upper end of the stem 27 and is connected with the main fuel supply conduit 14. The upper end of said stem 27 is provided with the fuel passage 29 through which the fuel flows into the main float chamber 19. Stem 30 is carried by the cover 25, and the elbow 33 is screwed on to the upper end thereof and connected to the suction conduit 16. Passages 34 and

35 are provided in said stem 30; the passage 34 opening into the elbow 33 and connecting the tank with the source of suction, an opening 36 being provided in the elbow with 110

which the passage 35 connects, so that this passage connects the tank with the atmosphere. A sleeve valve 37 is slidably mounted on said stem 30, and controls the passages or connections between the tank and the source of suction and the atmosphere.

The float 38 is slidably mounted on the stem 27, being provided with the upper and lower flanges 39 and 40, respectively, which 10 are secured together by the bolts 43 passing through the float 38. The hooks 44 extend upwardly from the flange 39 and are provided with laterally turned end portions 45, for the purpose hereinafter to be described. 15 A slot 46 is provided in the lower end of the stem 30, and lever arms 47 extending on opposite sides of the stem 27, and having their ends bent toward each other, are disposed in said slot 46 and pivotally connected to the 20 stem 30 by the pivot pin 48. The free ends of said lever arms are provided with slots 49 in which the laterally turned portions 45 of the hooks 44 engage. The arms 50 extend on opposite sides of the stem 30 and are pivotally mounted on the pin 48. The link 54 has its lower end disposed between the arms 50 and is connected thereto by the pin 53, passing through both arms, as clearly shown 25 in Figs. III and IV. A notch 55 is provided 30 in the upper end of the link 54, which notch engages the flange 56 on the sleeve valve, and said link is also provided with a longer notch 57, which is adapted to engage a stop flange 58 secured to and carried by the cover 35 25. Springs 59 are provided, connected at one end to the lug 60 on the lever arm 47, adjacent the slot 49 and, at the other end, to the tail 63 of the arm 50. A transverse passage 64 is provided in the lower end of 40 the stem 27 and communicates with an axial passage 65 in said stem. A T-coupling 66 is threaded on the lower end of stem 27 and engages the bottom of the chamber 19, the bottom of said chamber being clamped 45 against said T-coupling by means of a nut 67. A passage 68 is provided in said T-coupling and controlled by the flap valve 69, preventing the passage of the fuel from the auxiliary chamber 20 to the float chamber, 50 while permitting passage of fuel in the other direction. A stem 70 passes through the bottom of the auxiliary chamber 20 and is threaded into the T-coupling, said stem being provided with a passage 73, communicating 55 with the elbow 74, which is screwed on to the lower end of the stem 70 outside the auxiliary chamber, and to which is connected the conduit 18, leading to the carbureter so that fuel will flow by gravity from the 60 auxiliary chamber 20 through the conduit 18 to the carbureter.

A vent tube 75 is disposed within the float chamber 19, the lower end of said vent tube being connected with the opening 76 in the 65 bottom of the float chamber and the upper

end of said vent tube being connected to the opening 77, in the side wall of the float chamber 19, at a point above the fuel level therein, so that the auxiliary chamber 20 is always maintained under atmospheric pressure. 70

From the description of the parts given above, the operation of our device should be very readily understood. In Fig. II the valve 37 is shown in such position that the 75 connection between the tank and the source of suction is open while the connection with the atmosphere is closed. With the valve in this position, when the engine is running, the suction in the intake manifold will create 80 a partial vacuum in the tank and, since the main fuel supply tank 13 is open to the atmosphere and the fuel therein is under atmospheric pressure, the fuel will flow through the conduit 14 into the float chamber 85 19.

When the fuel in the float chamber 19 has risen to a predetermined level, so that the float has risen to the position shown in dotted lines in Fig. II, the ends of the lever 90 arms 47 being carried upwardly, each of the springs 59 carried thereby will also move upwardly, until the springs extend in a line passing above the pivot pin 48, when the springs will act to draw the levers 50 upwardly and to move the link 54 upwardly into the position shown in Fig. III, carrying the sleeve valve, shown in Fig. II, to the other position in which the connection between the tank and the atmosphere is open 95 100 and the connection between the tank and the source of suction is closed. When the valve is in this position, atmospheric pressure will be restored in the float chamber 19, and fuel will flow by gravity therefrom, past the flap 105 valve 69, to the auxiliary chamber 20, from which the fuel at all times feeds by force of gravity to the carbureter, since the auxiliary chamber 20 is always maintained under atmospheric pressure, due to the vent 110 tube 75. The auxiliary chamber 20 and the main float chamber 19 may be separately formed and may be assembled by nesting them together as shown in Fig. II, the stem 27 and the stem 70 together serving to secure 115 the cover 25 on the float chamber 19, and to hold the float chamber 19 in position closing the upper end of the auxiliary chamber 20, so that the two are secured together as a 120 unit.

We are aware that the particular embodiment of the invention here shown is susceptible of considerable variation without departing from the spirit of our invention, but we have found that this particular embodiment of the invention is desirable from many standpoints although we do not wish to limit the invention to the exact construction shown. 125

Having thus described our invention, what 130

we claim as new and desire to secure by Letters Patent is—

1. In a device of the class described, the combination of a tank; a float guide disposed longitudinally of said tank; a supply pipe leading to the tank; a stem carried by said tank and having passages therein connecting said tank with the atmosphere and a source of suction respectively; a sleeve valve slidably mounted on said stem and controlling said passages; a lever pivotally mounted on said stem and provided with a slot near its free end; an arm pivotally mounted on said stem; a spring connected at its ends to said lever and arm respectively; a link carried by said arm and connected to said sleeve valve; means for limiting the movement of said link; a float slidably mounted on said guide; and an arm carried by said float and having a laterally projecting portion disposed in the slot of said lever. 10
2. In a device of the class described, the combination of a tank; a float guide disposed longitudinally of said tank; a supply pipe leading to the tank; a stem carried by said tank and having passages therein connecting said tank with the atmosphere and a source of suction respectively; a sleeve valve slidably mounted on said stem and controlling said passages; a lever pivotally mounted on said stem and provided with a slot near its free end; an arm pivotally mounted on said stem; a spring connected at its ends to said lever and arm respectively; a link carried by said arm and connected to said sleeve valve; a float slidably mounted on said guide; and an arm carried by said float and having a laterally projecting portion disposed in the slot of said lever. 20
3. In a device of the class described, the combination of a tank; a float guide disposed longitudinally of said tank; a supply pipe leading to the tank; a stem carried by said tank and having passages therein connecting said tank with the atmosphere and a source of suction respectively; a sleeve valve slidably mounted on said stem and controlling said passages; a lever pivotally mounted on said stem; an arm pivotally mounted on said stem; a spring connected at its ends to said lever and arm respectively; a link carried by said arm and connected to said sleeve valve; a float slidably mounted on said guide; and a connection between said float and the free end of said lever. 30
4. In a device of the class described, the combination of a tank; a float guide disposed longitudinally of said tank; a supply pipe leading to the tank; a stem carried by said tank and having passages therein connecting said tank with the atmosphere and a source of suction respectively; a sleeve valve slidably mounted on said stem and controlling said passages; a lever pivotally mounted on said stem; an arm pivotally mounted on said 40
5. In a device of the class described, the combination of a tank; a float guide disposed in said tank; a supply pipe leading to said tank; a stem carried by said tank and having passages therein connecting said tank with the atmosphere and a source of suction respectively; a sleeve valve slidably mounted on said stem and controlling said passages; valve operating mechanism carried by said stem; a float slidably mounted on said guide; and connections between said float and said valve operating mechanism. 50
6. In a device of the class described, the combination of a tank; a supply pipe leading to said tank; a stem carried by the tank and having passages therein connecting said tank with the atmosphere and a source of suction respectively; a sleeve valve slidably mounted on said stem and controlling said 60
7. In a device of the class described, the combination of a tank; a stem provided with passages connecting said tank with the atmosphere and a source of suction respectively; a sleeve valve slidably mounted on said stem and controlling said passages; valve operating mechanism carried by said stem and a float mounted independently of the stem and operatively connected with said mechanism. 70
8. In a device of the class described, the combination of a tank; a stem provided with passages connecting said tank with the atmosphere and a source of suction respectively; a single valve controlling said passages; valve operating mechanism carried by said 80
9. In a device of the class described, the combination of a tank, a float guide disposed in said tank, a supply pipe leading to the tank, a stem projecting into said tank and having passages therein adapted to connect said tank with the atmosphere and a source of suction respectively, a valve slidably mounted on said stem and controlling said 90
10. In a device of the class described, the combination of a tank, a float upon said guide, a supply pipe leading to the tank, a stem projecting into said tank and having passages 100

therein connecting said tank with the atmosphere and a source of suction respectively, a valve slidably mounted on said stem and controlling said passages, a lever pivoted on said stem and having arms extending upon the opposite sides of said guide and connected with said float, arms pivoted upon said stem and extending in an opposite direction to said lever, springs connecting the last men-

tioned arms with the arms of said lever on 10 the opposite sides of the pivot point of said arms and lever, and a connection between said arms and said valve.

In testimony whereof we affix our signatures.

HERMAN R. SAXON.
GEORGE GANZERT.
